UNITED STATES PATENT OFFICE.

ALBERT GEORGE WORLEDGE, OF WESTCLIFF-ON-SEA, AND LOUIS SEBRIGHT, OF WIMBLEDON, ENGLAND.

PRINTER'S MECHANICAL QUOIN.

Application filed March 11, 1922. Serial No. 542,915.

To all whom it may concern:

Be it known that we, ALBERT GEORGE WORLEDGE, a British subject, residing in Westcliff-on-Sea, in the county of Essex, England, 5 and LOUIS SEBRIGHT, a British subject, residing in Wimbledon, in the county of Surrey, England, have invented certain new and useful Improvements in Printers' Mechanical Quoins, of which the following is a specification, reference being made to the accompanying drawings, forming a part thereof.

This invention relates to quoins as used by printers for locking up type in form or chase. They may be used however for any 15 other purpose where a mechanically expanding device is required.

Steel screw quoins as hitherto made have usually comprised a pair of similar blocks or plates adapted to be forced apart by one 20 or more steel wedges working against inclined planes on the said blocks, the wedges being drawn up as required by means of screw bearings against shoulders on the blocks and adapted to be turned by a key. 25 The blocks have been guided in their expanding movements by studs with heads thereon engaging in countersunk recesses in the blocks, the heads of the studs limiting the expanding movement, so that the maximum 30 expansion was rather less than the width of one of the blocks. Usually the head at one end of each stud was screwed on, and if the heads came off the blocks could fall apart, while the wedge piece could always fall out 35 when its screw was removed.

It is the object of the present invention to provide an improved form of screw quoins, for whereas the maximum expansion for a given size of quoins has only been equal to 40 one of the blocks hitherto, the amount now obtainable by the present invention is almost equal to the combined thickness of two blocks, and also to provide a quoins that when it is between the type and chase, the majority 45 of its expansion can be controlled easily and quickly by the thumb or finger of one hand through the aid of its key lever in the other hand, constituting a far greater degree of usefulness. A further object of the invention is to provide a quoins that can be assembled 50 easily and then securely locked together against accidental dis-assembly. For this purpose a double-ended milled head screw having on one end a right hand thread and 55 on the other a left hand thread, controls the

movements of two taper-sided nuts acting as wedges one at each end between two expanding blocks having their ends inclined at an angle corresponding with the taper sides of the nuts. These wedge nuts are also provided with projecting edges or tongues which engage the grooves at the top and bottom of the inclined ends of the blocks and so guide them in their opening or closing movement, but further guides are informed at 60 the bottom of the quoins whereby each block is provided with portions extending toward each other, those on one block sliding between those on the other so as to keep the expanding blocks parallel to each other, or 65 as a modification these guides or extending portions may be dispensed with to allow the blocks to adjust themselves between surfaces that are not parallel. A small screw is also inserted into the bottom of one thread each 70 side of the milled head to act as a stop to prevent the quoins falling to pieces by being opened beyond its practical limit. A key to operate the quoins has a wide end bent at right angles for use as a lever to press back 75 the type as far as possible while the screw of quoins is being turned with the thumb or finger and the other end is shaped to fit the holes in the milled-head whereby the final pressure may be exerted to securely lock the 80 type in form or chase.

Referring to the accompanying drawings:—

Fig. 1 is a perspective view of the quoins when closed.

Fig. 2 is a perspective view when open,

Fig. 3 an underside view of the quoins and

Fig. 4 is the operating key.

The quoins of the present invention comprises two blocks C, C' that are adapted to 90 be moved towards and from each other as is common in the art. Said blocks are positioned on opposite sides of a pair of screws which are adapted to be rotated by a rotary head A. Carried on said screws and positioned between said side blocks C, C', are nuts B, B' which act as wedge blocks, each of the side blocks being cut away or recessed, as at F, for the accommodation of said 95 wedge blocks B, B'.

In accordance with the present invention, the opening and closing movements of the side blocks C, C', are effected by means that lend to convenience in the assembly of the quoins. Such means consist of cooperating 100

105

110

grooves and ridges in the wedge and side blocks, ridges or ribs *b* being formed in pairs on the tops and bottoms of one set of blocks and corresponding grooves *c* being formed 5 in the other set of blocks. Preferably the ribs *b* are on the wedge blocks *B*, *B'*, and the grooves *c* in the side blocks *C*, *C'*, as shown. Each pair of ribs *b* and each pair of grooves *c* diverge outwardly, so to speak, from the 10 head *A* so that by turning head *A* to move the wedge blocks towards said head, the side blocks will be moved apart while a reverse movement of said head and wedge blocks will, of course, bring or close the side blocks 15 together.

Such an arrangement has many advantages. The quoin can readily be assembled, it only being necessary to run the wedge block *B*, *B'* on the screws up close to head *A* 20 where the ribs *b* and grooves *c* will be in registry after which the nuts or wedge blocks *B*, *B'*, are moved out from the head and the ribs will enter the grooves and the quoin will be assembled. Furthermore, after the quoin 25 is thus assembled, it may easily be locked against accidental dis-assembly by merely inserting a small screw *E* in each of the large screws at a point near head *A* where the movement of wedge blocks *B*, *B'* toward 30 the head will be so limited as to prevent the ribs *b* being run out of the grooves *c*. Accidental dis-assembly of the quoin by a movement of the nuts towards head *A* is thus prevented while dis-assembly of the parts by a 35 movement of said nuts away from the head is prevented by the side blocks *C*, *C'* being brought together when the wedges are moved outward. Additionally, the easy manner of 40 assembly permits the use of elongated ribs and grooves and the formation of the ribs integrally with their associated blocks, all of which imparts a desired characteristic, i. e., 45 rigidity, to the assembled quoin.

To further add to the rigidity of the 45 quoin, the bottom of one of the side blocks is cut away to receive laterally extending bottom portions of the other side blocks, as shown in Figs. 2 and 3, the extensions *K*, *K'* of one of said blocks being clearly shown in 50 Fig. 3.

As an aid in manipulating the head *A* and the associated screws, there is provided a key 55 *D* (see Fig. 4) one end of which is bent at right angles to the intermediate portion and widened as at *G* so that it may be inserted between the type and the inside edge of the chase and pressure applied to compress the type while the quoin is being expanded easily and quickly with the thumb or finger. 60 After all slackness has been thus taken up, the key *D* may be withdrawn and the opposite end *H* thereof, which is comparatively small, inserted in holes in head *A* to turn said head and give the final necessary pressure to securely lock the type. 65

What we claim as our invention is:—

1. In a printer's quoin, the combination of a right hand screw, a left hand screw, a rotary head between said screws for rotating the latter, a screw threaded wedge on 70 each screw, each wedge having integral divergent ribs formed thereon, and side blocks arranged on each side of the screws and having divergent slots therein for the reception of the ribs on the wedges, said slots 75 intersecting the side edges of said blocks, and said side blocks being movable toward each other by moving the wedges away from said head, whereby outward movement of said wedges is limited by the side blocks. 80

2. In a printer's quoin, the combination of a right hand screw, a left hand screw, a rotary head between said screws for rotating the latter, a screw threaded wedge on 85 each screw, diverging ribs on each screw threaded wedge, side blocks arranged on each side of the screws and having divergent slots therein for the reception of the ribs on said wedges, and means on said screws for limiting the movement of the wedges whereby accidental displacement of said ribs from said slots is prevented. 90

3. In a printer's quoin the combination with a rotatable head, of a right handed screw on one end of the head, a left handed 95 screw on the other end of the head, oppositely inclined wedge-shaped members on the two screws, side blocks arranged on opposite sides of the screw, oppositely inclined surfaces on each block adapted to be engaged by the wedge-shaped members, projections on the wedge-shaped members and recesses on the side blocks to receive said projections to retain the side blocks and wedges in position to form an integral body. 100

4. In a printer's quoin, the combination of a pair of oppositely threaded screws, a rotary head for rotating said screws, a wedge block on each screw, a side block on 110 each side of the screw adapted to engage the wedge blocks, and cooperating elements on said wedge and side blocks for separating the side blocks, said cooperating elements extending diagonally of and intersecting the side edges of said blocks, and said side blocks being movable toward each other by moving the wedges away from said head, whereby outward movement of said wedges is limited by the side blocks. 115

5. In a printer's quoin, the combination of a pair of oppositely threaded screws, a rotary head for rotating said screws, side blocks on opposite sides of the screws, wedge blocks on the screws and movable away from the rotary head to bring the side blocks together, whereby the side blocks when closed together will limit the outward movement of the wedge blocks, and means for limiting the movement of the wedges towards the rotary head whereby the sepa- 125 130

ration of the side blocks is limited and accidental dis-assembly of the quoin is prevented.

6. In a printer's quoin, the combination 5 of a pair of oppositely threaded screws, a rotary head for rotating said screws, side blocks on opposite sides of the screws, wedge blocks on said screws and movable toward the rotary head for moving the side blocks 10 away from each other, cooperating elements on the wedge and side blocks for effecting the separation of the side blocks, said cooperating elements being disengageable by moving the wedge blocks toward the rotary 15 head and moving the side blocks away from each other, and removable means for limiting the said movements of said wedge and

side blocks to prevent accidental disengagement of said cooperating elements.

7. In a printer's quoin, the combination 20 of a pair of oppositely threaded screws, a rotary head for rotating said screws, a side block on each side of said screws, wedge blocks on said screws, and cooperating elements on said wedge and side blocks for effecting separation of the side blocks upon 25 movement of the wedge blocks toward the rotary head, said cooperating elements being disengageable by moving the wedge blocks towards said head and moving the 30 side blocks away from each other.

ALBERT GEORGE WORLEDGE.
LOUIS SEBRIGHT.
